UNITED STATES PATENT OFFICE.

OSCAR B. CARLSON, OF OAK PARK, ILLINOIS.

AIR CUSHION.

Application filed March 5, 1925. Serial No. 13,036.

This invention relates to air mattresses or other cushions of the inflatable type, and the primary object of this invention is to provide a novel construction for an inflatable air cushion or mattress, of such a character that weight placed upon one part will not effect bulging of the cushion in another part.

In attaining this object, I provide, within a suitable air-tight envelope, a reinforcing structure composed of separate series of transverse and longitudinal bands of inelastic material spaced apart uniformly with relatively short intervals between them. Opposed networks are thus formed with their intersections arranged oppositely so that they may be secured together at such intersections by means of vertical stays whereby effectively to resist distortion of the mattress in use.

A general object is to provide a mattress of such a character that it may be manufactured on a practical and economical basis.

In the drawings, Figure 1 illustrates in perspective an air cushion or mattress, a portion of the mattress covering being shown removed to illustrate the preferred form of reinforcement.

Fig. 2 is a detail cross section of the mattress taken substantially on the line 2—2 of Fig. 1 showing the character and method of securing the cross stays.

Figs. 3, 4 and 5 are detail views showing various methods for arranging the network at the corners.

In the drawings there is shown a series of bands 6 which run longitudinally about the cushion preferably in equally spaced relation. A similar series of bands 7 run transversely around the cushion in equally spaced relation. The series of bands 6 and the series of bands 7 are preferably each arranged with the same spacing distance whereby a plurality of squares is formed by their intersections. The material of the bands is preferably of non-elastic fabric such as webbing.

A variety of arrangements may be used at the edges and corners. Herein, the edge bands are part of the series 6 and 7, but are adapted to provide a suitable edge. At the edge of the cushion the longitudinal edge bands 8 are turned to form a right-angular strip having the part 9 at the large faces of the cushion and the part 10 at the side or edge faces as shown in Figs. 3, 4 and 5. The transverse series of bands likewise has its edge bands 11 similarly turned to provide parts lying on rectangular faces of the cushion as

indicated at 12 and 13. Such a construction will, of course, result in a double thickness of webbing at each corner 15 thus providing additional strength which, of course, is desirable. In turning the edge bands in the manner described, there will of course, be a loose ear 14 (Fig. 4) of webbing formed on the side faces of the cushion. This ear may be flattened out and sewed down to the parts 10 and 12 as illustrated at 16 in Fig. 4. Likewise the ear may be cut away by a V-shaped cut and the cut edges 17 and 18 (Fig. 5) be sewed together as shown at 19 in Fig. 5. Or, otherwise, the ear may be cut into by a straight cut and the ends 20 and 21 (Fig. 3) be overlapped and sewed together as shown at 22 in Fig. 3.

The above construction thus provides a plurality of strips at the edge of the cushion comprising the corners 15 and portions of the bands 6 and 7. According to the thickness of the mattress, additional reinforcing means may be put around these strips. Such a construction is here shown as a single band 23 about the edge or side faces of the cushion secured to the vertical strips.

By reason of the above described construction the two faces will present a duplicating array of squares on the top and bottom of the mattress. The overlying or opposing intersections, as for example, 24 and 25 (Fig. 2) are connected together by flexible stays 26 preferably of webbing similar to the bands 6 and 7 or of other non-elastic material. The stays 26 are made the same length as the edge strips when it is desired that the cushion assume a truly box shape. Of course, any desired shape may be produced.

The method of securing the stay strips 26 may vary in a number of practical ways each of which is suitable to effect the desired strength for tension in the connection of the stays to the bands. In Fig. 2 I illustrate one method of doing this. The longitudinal bands 6 in the present instance lie on top or outside of the transverse bands 7. Each stay 26 has its ends 27 and 28 interposed between the intersecting bands so that the edge 29 of the band 7 supports the fold 30 in the stay 26. Stitches 31 pass through the two bands 6 and 7 and the ends of stay 26 thus securing the parts firmly together into a rigid structure. Of course, the band 23 is also stitched to the bands 6 and 7 at the intersections 32, the band 23 being outside the side strips.

This supporting network of webbing is

used as a base upon which an airtight material 33 is secured, preferably by sewing the material to each strip support all over the structure. The material 33 is sewed together 5 forming a closed envelope in any desired manner. The stitchings and seams in the airtight envelope 33 are treated to ensure non-leakage at these points. An air valve 34 is provided by which inflation and deflation 10 may be accomplished.

The outside of the air envelope is suitably covered as by an outside covering material 35. This construction provides a cushion which is so formed that expansion of the 15 same cannot take place beyond the limits set by the lengths of the non-elastic supporting webbing. When weight is placed on the cushion at any local point the compression is transmitted equally to the interior of the envelope but no bulging will take place in the cushion because of the inability of the material to expand.

In addition to the structure above described, I may provide other supports mid-way through the cushion from edge to edge. 25 In the present instance these are strips which are substantially half the width of the outer strips 6 and 7 and which are parallel to strips 6 and 7. These do not appear in Fig. 1 because of the confusion of lines representing the outside bands, but are shown in Fig. 2 in the preferred and practical relationship to the remainder of the network. Transversely 30 of the cushion parallel with the bands 7 are vertically disposed strips 36 sewed at 37 to the vertical stays 26. The strips 36 in the present instance lie below the median plane of the cushion. Above the median plane are longitudinal stays or strips 38 lying in vertical planes adjacent the edges of the vertical stays 26. A right angled insert 39 is sewed at 40 to the strip 38 and at 41 to the vertical stay 26.

Fig. 3 shows one way in which the end 42 45 of strip 38 may be secured between the vertical part of the strip 6 and the outside edge band 23. Likewise, Fig. 5 shows how the end 43 of the band 36 may be secured between the band 23 and the vertical portion of the band 50 7. Because the bands 36 and 38 are respec-

tively below and above the median plane of the cushion, it is obvious that it is advantageous to provide these bands substantially half as wide as the outside strips forming the network. Of course, it will be understood 55 that this construction can be varied so as to provide any other form of mid-staying webs for the edges of the cushion to prevent bulging thereof.

While the construction herein illustrated 60 has been shown and described somewhat in detail, it is to be understood that the invention is not limited to the full details of construction but that other embodiments of the invention are contemplated as will be more apparent 65 from the scope of the appended claim.

I claim as my invention:

A pneumatic mattress comprising, in combination, a substantially rectangular inflatable envelope having top, bottom and edge walls, and a reinforcing structure enclosed within said casing adapted to hold it against distortion when inflated, said structure comprising two series of bands within said envelope each adapted in the inflated condition of 70 the envelope to form a substantially rectangular loop, the bands of one series being equidistantly spaced apart and disposed at right angles to the bands of the other series which are similarly spaced whereby to form networks upon the inner surfaces of the bottom and top walls of the envelope and vertical stays at the inner surfaces of the edge walls of the envelope, two series of perpendicularly disposed reinforcing strips forming a third 75 network intermediate the upper and lower networks, the ends of the strips of the last mentioned series being secured to the vertical stays formed at the opposite ends of each of said bands, additional reinforcing strips 80 extending along the upper and lower corners of the envelope and connecting said bands, and reinforcing stay strips extending up and down within the interior of the envelope and 85 connecting the three networks, all of said bands and strips being made of flat strips of substantially nonelastic material.

In testimony whereof, I have hereunto affixed my signature.

OSCAR B. CARLSON.
